United States Patent

Des. 235,824
Patented July 15, 1975

235,824

MERCHANDISE DISPLAY STAND

David A. Long, 7723 Mill Road,
Elkins Park, Pa. 19117

Filed Jan. 25, 1974, Ser. No. 436,833

Term of patent 14 years

Int. Cl. D20—02

U.S. Cl. D6—28

FIG. 1

FIG. 2

FIG. 1 is a top perspective view of the merchandise display stand showing my new design; and

FIG. 2 is a bottom perspective view thereof and taken from the side opposite that shown in FIG. 1.

I claim:

The ornamental design for a merchandise display stand, substantially as shown.
